UNITED STATES PATENT OFFICE.

MARTIN S. HOY, OF WILKINSBURG, PENNSYLVANIA.

PROTRACTOR.

SPECIFICATION forming part of Letters Patent No. 606,344, dated June 28, 1898.

Application filed March 18, 1897. Serial No. 628,121. (No model.)

To all whom it may concern:

Be it known that I, MARTIN S. HOY, a citizen of the United States, residing at Wilkinsburg, in the county of Allegheny and State of Pennsylvania, have invented certain new and useful Improvements in Mechanical Dividers; and I do hereby declare the following to be a full, clear, and exact description of the invention, such as will enable others skilled in the art to which it appertains to make and use the same.

This invention relates to improvements in protracting-bevels, and to this end provides a mechanical divider consisting practically of a quadrant one member or radius of which is provided with a slot, the said quadrant having certain subdivisions employed in connection with the bevel-stock or pivoted ruler, also carrying subdivisions, all as will be herein-after fully set forth in the specification and the novel features specifically pointed out in the claim.

In the accompanying drawings, forming part of this specification, Figure 1 is a plan view of an instrument constructed in accordance with my invention. Fig. 2 is an enlarged detail view of a quadrant, showing subdivisions thereon. Fig. 3 is a similar view of the bevel-stock or ruler. Fig. 4 is a sectional view through the implement. Fig. 5 is a detail view of the attachment which provides for holding the adjustment of the bevel-stock or ruler.

Referring to the drawings by numerals and letters, 1 designates a quadrant presenting an angle or square having a blade 2 and tongue 3, the blade being extended beyond the segment and the tongue having a longitudinal slot 4. Through this slot passes a thumb-screw 5, connecting an attachment 6 and a bevel or ruler 7 in sliding connection with the quadrant, these parts having heads 8 and 9, respectively, which are provided with segmental slots that are engaged by a thumb-screw 10 for holding these parts adjusted. The blade or tongue 11 of the bevel is secured to the head 8 by screws, leaving a space between the attachment and blade or tongue to receive the tongue of the angle or square of the quadrant. The attachment is provided adjoining its head with guide-rollers 12, 12, that bear against the outer edge of the tongue of the

square or angle and hold the said attachment at the proper relative position.

As shown in the drawings, the blade 2 of the square or angle of the quadrant is divided by longitudinal and transverse lines into a plurality of spaces. For the purpose of illustration we will suppose that the said blade is twenty-four inches in length and the transverse lines *a* one-twelfth of an inch apart. The said blade is then provided with a scale containing graduations from "1" to "288." The blade is also provided with sixteen parallel lines *b*, extending longitudinally the entire distance. Thus it is possible in computing and measuring to return from the point of the blade to the heel, skipping a space in the second line for the miter of the square, and starting with "290," then proceed outward to the point again. This can be proceeded with or continued through the sixteen longitudinal divisions, so that the blade is capable of four thousand six hundred and eight graduations or divisions. The tongue of the angle or square is marked in the same manner, with the exception that it is but sixteen inches long, and therefore the transverse lines *c* or graduations would only run to "192" and, coming back to the heel, would start with "194" on the second and proceed or continue in this manner. The number of longitudinal lines *b* is limited to eight spaces, owing to the slot 4, and these spaces or graduations are on the same scale as those on the blade. The blade of the bevel or ruler is marked with lines *e*, *f*, that are graduated similar to those on the blade and the tongue of the square or angle, having sixteen longitudinal lines *e* and transverse lines or graduations *f*, running from "1" to "400," the second series being graduated from "2" to "800," and so on until all the spaces are filled. On the other side of the square the tongue is provided with a scale the marks *g* of which are one-twelfth of an inch apart and with eight parallel lines *h*, while the blade is marked with spaces or lines *i* and *k* in the ratio of one to 3.1416. On the same side, which is sixteen-inch radius from the heel of the square to the trammel-point of each tongue and blade, two radial lines *l* are made, so as to permit the indication of the degrees from "1" to "90" and return, so that the operator can obtain any degree within a quadrant. By providing an

implement constructed as herein shown and described the bevel or ruler can be brought to the miter of the square and the attachment firmly held in place by the thumb-screw. 5 Then the head or bevel may be brought around to its full capacity, throwing it at right angles with the blade or square and parallel with the tongue thereof. This will give the operator any desired degree in a 10 quadrant. Now should the operator wish to find the hypotenuse of a right-angle triangle he can do so by setting the bevel or ruler on tongue of square or angle for one side of the right angle and to a point on blade of square for the other side, the blade or tongue of the bevel or ruler giving the answer. It 15 will also be apparent that the ruler and attachments which are applied to the quadrant could be removed, and by providing said attachment with a central opening instead of the segmental slot this part of the instrument could be readily used as a T-square.

Having thus described my invention, what

I claim as new, and desire to secure by Letters Patent, is—

25

The quadrant provided with the slot 4, the blade 2 extending at one end beyond the quadrant, the head 6 secured to one corner of the quadrant and provided with the curved slot at its outer end, and the friction-rollers 30 12 which bear against the outer edge of the tongue of the square or angle, combined with the bevel or rule 11, the slotted head 8 secured to its inner end, and which head 8 corresponds in shape and size to the head 9; and 35 the clamping-screw which passes through the head 9, the slot 4 in the tongue and the rule, substantially as shown and described.

In testimony whereof I have signed this specification in the presence of two subscribing witnesses.
